CLAIM

The ornamental design for a store display bracket, as shown and described.

DESCRIPTION

FIG. 1 is a top right perspective view of a store display bracket showing my new design;

FIG. 2 is a front elevational view thereof;

FIG. 3 is a right side elevational view thereof, with the left elevational view being a mirror image thereof;

FIG. 4 is a rear elevational view thereof;

FIG. 5 is a top plan view thereof;

FIG. 6 is a bottom view thereof;

FIG. 7 is a top right perspective view of a store display bracket showing a modified embodiment of my new design;

FIG. 8 is a front elevational view thereof;

FIG. 9 is a right side elevational view thereof, with the left side elevational view being a mirror image thereof;

FIG. 10 is a rear elevational view thereof;

FIG. 11 is a top plan view thereof; and,

FIG. 12 is a bottom view thereof.
